US00D753142S

(12) United States Design Patent
Hwang et al.

(10) Patent No.: US D753,142 S
(45) Date of Patent:  Apr. 5, 2016

(54) DISPLAY SCREEN OR PORTION THEREOF
WITH GRAPHICAL USER INTERFACE

(71) Applicant: Samsung Electronics Co., Ltd.,
Suwon-si, Gyeonggi-do (KR)

(72) Inventors: Woo-Seok Hwang, Seoul (KR);
Yong-Hwan Kwon, Sungnam-Si (KR)

(73) Assignee: SAMSUNG ELECTRONICS CO.,
LTD. (KR)

() Term: 14 Years

(21) Appl. No.: 29/489,303

(22) Filed: Apr. 29, 2014

(30) Foreign Application Priority Data

Dec. 30, 2013 (KR) 30-2013-0066501

(51) LOC (10) Cl. 14-04

(52) U.S. Cl.

(57) CLAIM

The ornamental design for a display screen or portion thereof with graphical user interface, as shown and described.

DESCRIPTION

FIG. 1 is a front view of a display screen or portion thereof with graphical user interface, showing our new design; and, FIG. 2 is a front view thereof, as shown in a display screen environment.

The broken lines are for environmental purposes only and form no part of the claimed design.
